ATTORNEY

UNITED STATES PATENT OFFICE.

ADOLPH L. MITCHELL, OF BROOKLYN, NEW YORK.

CAN OR JAR TOP COVER.

SPECIFICATION forming part of Letters Patent No. 395,289, dated December 25, 1888.

Application filed April 16, 1888. Serial No. 270,750. (Model.)

To all whom it may concern:

Be it known that I, ADOLPH L. MITCHELL, of Brooklyn, county of Kings, and State of New York, have invented certain new and useful Improvements in Can or Jar Top Covers, of which the following is a full, clear, and exact description, reference being had to the accompanying drawings, and to the letters of reference marked thereon.

10. My invention consists of an improved contrivance for a packing cover for cans, jars, bottles, and other like articles, by which the mouth of the can, jar, or other like article may be more readily sealed or packed hermetically when closed than others now in use, and may likewise be continuously or repeatedly used to better advantage, said contrivance being essentially a packing-disk of elastic material fitted movably in retaining-grooves 15 in the lower side of the cover, so that it closes the mouth of the can, jar, or other article when the cover closes, together with the cover so fitted with the packing and with its fastenings to the can-top, that it is made to wedge the packing tight by a slight lateral shift after being closed on the mouth, all as follows, referring to the accompanying drawings, in which—

20. Figure 1 is a sectional elevation of a can-top with my improved cover, said cover being closed. Fig. 2 is a side elevation of the same with the cover shifted preparatory to releasing the packing for opening the mouth, and showing the cover partly raised in dotted lines. 25. Fig. 3 is a transverse section of the cover on line $x-x$ of Fig. 1; and Fig. 4 is a sectional elevation of a small can, also fitted with my improved cover. Fig. 5 is a sectional elevation of the can on the line $x-x$, in Fig. 4.

30. The cover a carries a packing-disk or other suitably-shaped piece, b , of elastic material, fitted adjustably to it in grooves c , or it may be any other improved means of holding it so that it may shift in the cover, or the cover 35 may shift along the packing a short distance after closing down on the mouth of the top d of the can or other article. Said cover is pivoted in vertically-inclined slots e of the can-top f , or by such slots in itself on a fixed pivot,

40. g , of the can-top, and has spurs i at its opposite end, which engage with inclines j of the can-top at the free end, so that after closing the cover it may then be shifted along the inclines and along the packing, whereby the inclines draw or wedge the cover and packing 45 down securely and hermetically tight on the mouth, and hold the same permanently until the cover is shifted laterally and upwardly along the inclines again for releasing the packing and opening the cover.

40. It will be seen that the cover is alike held or forced down at the four corners in such manner as to insure substantially uniform effect all round for making the packing tight at all points.

45. The packing is designed to be so fitted in the grooves c that it will be retained by friction anywhere that it may be left, but so that it will not obstruct the shifting of the cover. This insures the return of the packing to the 50 mouth of the can when the cover is closed in the same relation thereto that it left said mouth when opened.

50. The grooves in the cover for retaining the packing may be formed in any approved way, as by casting integral retaining lugs or flanges with the cover, as I have represented them in the drawings, or they may be bent inward from the lower edge of the cover, or be soldered on or otherwise attached, as 55 preferred.

50. The vessels which I have represented are such as are usually made of metal whereon the tops, also made of metal, are usually soldered to the neck of the can. In the application of the invention to bottles and glass or earthen jars the top will probably be fastened with cement.

55. What I claim, and desire to secure by Letters Patent, is—

60. 1. The improved hermetically-sealing can-top comprising the laterally-shifting cover, inclined fastening devices wedging or binding said laterally-shifting cover on the can-top, and the interposed packing of elastic 65 material fixed movably in retaining-grooves in the lower side of the cover, substantially 70 as described.

2. The improved hermetically-sealing can-top comprising the laterally-shifting pivoted cover, inclined fastening devices wedging or binding said laterally-shifting cover on the
5 can-top, and the interposed packing of elastic material fixed movably in the cover, substantially as described.

In testimony that I claim the foregoing I have hereunto set my hand in the presence of two witnesses.

ADOLPH L. MITCHELL.
